UNITED STATES PATENT OFFICE

128,651

DESIGN FOR A PICTURE FRAME

Anthony Vander Werf, Yonkers, N. Y.

Application March 10, 1941, Serial No. 99,464

Term of patent 7 years

To whom it may concern:

Be it known that I, Anthony Vander Werf, a citizen of the United States, residing at No. 29 Cowles Avenue, city of Yonkers, in the county of Westchester, State of New York, have invented a new, original, and ornamental Design for Picture Frames, of which the following is a specification, reference being had to the accompanying drawing, forming part thereof.

Fig. 1 is a front elevational view of a picture frame showing my new design; and

Fig. 2 is a right-hand edge view; and
Fig. 3 is a left-hand edge view.

I claim:

The ornamental design for a picture frame, substantially as shown.

ANTHONY VANDER WERF.
